UNITED STATES PATENT OFFICE

HENRY ROBINSON, OF NEW YORK, N. Y.

SPINACH, ETC., WASHING MACHINE

Application filed April 14, 1930. Serial No. 444,306.

My invention relates to a machine of the general character disclosed in Letters Patent of the United States issued to me on March 25, 1930, for agitating etc. machines, Nos. 5 1,752,202 and 1,752,203.

An important aim of the present invention is to provide a machine of such construction that will effectively wash or agitate spinach, other leafy vegetables or the equivalent, that 10 can be manufactured at minimum cost and is exceedingly durable, and which enables me to use an agitator having arms which are radially straight.

Another object is to provide a construction 15 which will permit maximum drainage or passage of the water through the saucer-shaped disk used, especially at its sides.

A further object is to provide a construction 20 wherein the agitator extends across the junction line of and substantially in contact with the said disk and the agitating chamber wall.

The more specific objects and advantages 25 will become apparent from a consideration of the description following taken in connection with accompanying drawings illustrating an operative embodiment.

In said drawings:

Figure 1 is a view partly in front elevation 30 and partly in central vertical section through a machine constructed in accordance with my invention;

Figure 2 is a horizontal sectional view taken on the line 2—2 of Figure 1;

Figure 3 is an end elevation of the agitator 35 which may be employed, and

Figure 4 is an end elevation of a modified form of agitator.

Referring specifically to the drawings 40 wherein like reference characters designate like or corresponding parts, and first to Figures 1 to 3 inclusive, 10 designates a base or bowl which is preferably made in a single metallic casting and has an upstanding marginal wall 11 and a central hollow bearing 12 terminating below the upper edge of said wall.

Said wall 11 at suitable intervals along 45 its inner surface and below the top, has open socket members 14 integral therewith, the

cavities thereof being designated 15. Removably surmounting the wall 11 is a cylinder or chamber member 16 which also is preferably a single metallic casting.

The cylinder 16 forms a chamber in which 55 the spinach, other leafy vegetables or the equivalent are received, agitated and washed. Such cylinder 16 is thickened at its lower edge which provides a shoulder 17 to rest on the wall 11, an annular depending flange 60 18 inwardly thereof and telescoping into bowl 10 and a shoulder 19 in line with shoulder 17 but on the opposite side of said flange 18. At 20 the cylinder is provided with a removable cover and at 21 has a conventional 65 closure or door over a discharge opening.

Journalled in bearing 12 is an operating shaft or spindle 22 which projects above said bearing 12 through an opening in a stationary foraminous saucer-shaped disk or tray 70 23 and into a hub 24 of an agitating element 25. A set screw 26 is shown as one means of securing the agitator element to the shaft 22.

Said disk or tray 23 is removable and has 75 its side or marginal wall 27 spaced from the wall 11 and flange 18 to enable maximum drainage through the perforations in said wall 27. To further aid in drainage, the inner surface of wall 27 is inclined as shown 80 and the adjacent portion of the main wall of the cylinder 16 at 28 is inclined and merges into or is flush with the inner surface of wall 27.

Integral lugs 29 of any desired number 85 extend from the disk or tray 23 into the previously mentioned cavities 15 of socket members 14, in order to removably mount said disk or tray against rotation. Any other desired type of means to accomplish 90 the same end may be used.

Said bearing 12 has a shoulder 30 on which the disk or tray 23 rests while a reduced portion 31 on said bearing extends through and above the disk 23 into the hub 24 to exclude 95 water and foreign matter from the bearing.

The agitator 25 is preferably but not necessarily made in a single piece or casting and diametrically on opposite sides of its axis has agitator blades 32, one being ar- 100

ranged reverse to the other as best shown in Figure 3. Such blades 32 are radially straight and preferably of the same width throughout and their end edges as shown in 5 Figure 1 are preferably inclined to closely conform to the inner surface of the flange 27 and the portion 28. In addition, the blades are of a height to overlap or extend both above and below the junction line occurring 10 at the shoulder 19 which rests on the wall 17, to keep all materials agitated and prevent their lodging between the wall 27 and said shoulder 19. Said blades 32 may be flat as 15 shown in Figure 3 but if preferred they may be dished or concave as at 33, as shown in Figure 4, the other equivalent parts having primed reference characters. Such an agitator I find very efficient in the washing of 20 spinach or the equivalent and exceedingly durable and capable of manufacture at very low cost.

The drive shaft 22 may be driven in any suitable manner and for instance by the mechanism disclosed in my copending application Serial No. 429,156, filed February 17, 25 1930.

Simultaneously with operation of the agitator, water preferably continuously flows from any desired source through a nozzle 34 under control of a valve 35, into chamber 30 16, such water and foreign matter discharging or draining through a pipe 36 coupled to the cylinder.

Aside from the agitator and the disk 23, 35 certain details of the parts may be considered as divided out of the application for the aforesaid Patent 1,752,202.

Presuming operation of the machine, water continuously flows through nozzle 34 into 40 the cylinder and onto and through the spinach or equivalent material therein, such material being supported by the disk 23. At the same time, the agitator 25 through its radially straight blades 32 produces the necessary 45 centrifugal and centripetal motion to move the spinach for thorough washing or cleansing thereof, the water and foreign matter escaping through the perforations of the disk, the particular construction especially enabling the escape of the water and 50 foreign matter through the side of the disk as at the wall 27.

Various changes may be resorted to provided they fall within the spirit and scope of 55 the invention.

I claim:

1. A machine of the class described having a cylinder, a bowl-shaped base for said cylinder, a disk to support material in said 60 cylinder to be washed, said disk having a marginal perforated wall inclined and spaced from the adjacent portion of the cylinder, said disk being overlapped by said cylinder, said cylinder and base being separable to enable operative positioning of the disk, and

an agitator movable over said disk to cause discharge through the marginal perforated wall.

2. A machine of the class described having a cylinder, a bowl-shaped base for said cylinder, a perforated disk to support material in said cylinder to be washed, said cylinder and disk having side wall surfaces substantially angularly disposed and merging with each other, the side wall of said disk being 70 perforated, said disk being overlapped by said cylinder, said cylinder and base being separable whereby the disk may be operatively positioned, and an agitator movable over the disk.

3. A machine of the class described having a cylinder, a bowl-shaped base for said cylinder, a perforated disk in said base to support material to be washed, said cylinder and disk having side wall surfaces substantially angularly disposed and merging with each other, the side wall of said disk being perforated, and an agitator movable over the disk, and blades on said agitator whose end walls substantially conform to the angle 80 of said surfaces.

4. A machine of the class described having a cylinder member, a bowl-shaped base member therefor, a disk in one of said members to support material to be washed and permit 95 drainage of water therefrom at the bottom and at the side wall into the bowl-shaped base, the side wall of the disk being perforated and inclined upwardly and outwardly, the adjacent wall surface of the cylinder being similarly inclined, said side wall below its top being spaced from the side wall of the cylinder, said disk being overlapped by said cylinder, said cylinder and base being separable whereby the disk may be operatively positioned, and an agitator movable over 100 said disk.

5. A machine of the class described having a cylinder member, a bowl-shaped base member therefor, a disk in one of said members to support material to be washed and permit 110 drainage of water therefrom into the bowl-shaped base, the side wall of the disk being perforated and inclined upwardly and outwardly, the adjacent wall surface of the cylinder being similarly inclined, said side wall below its top being spaced from the side wall of the cylinder, and an agitator movable over 115 said disk, the free end walls of the blades of the agitator being inclined substantially in conformity with the inclination of said side wall.

6. A machine of the class described having a cylinder member, a bowl-shaped base member therefor, a disk in one of said members to support material to be washed and permit 125 drainage of water therefrom into the bowl-shaped base, the side wall of the disk being perforated and inclined upwardly and outwardly, the adjacent wall surface of the cylinder 130

inder being similarly inclined, said side wall below its top being spaced from the side wall of the cylinder, and an agitator movable over said disk, said agitator having substantially radially straight blades extending above and below the top of said side wall, and the free end walls of the blades being inclined substantially in conformity with the inclination of said side wall.

10 7. A machine of the class described having a cylinder, a bowl-shaped base for said cylinder, a disk to support material in said cylinder to be washed, said disk having a marginal perforated wall overlapped by the cylinder and spaced from the adjacent portion of the bowl, said base and cylinder being separable, and an agitator movable over said disk to cause discharge through the marginal perforated wall.

15 20 In testimony whereof I have affixed my signature.

HENRY ROBINSON.
